SURFACE ORNAMENTATION OF WALLS, &c.

No. 16,530.

Patented Feb. 16, 1886.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,530, dated February 16, 1886.

Application filed November 13, 1885. Serial No. 182,709. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part hereof.

Upon the surface are quadrangular rhombical elevations A, arranged in rows B in a lateral direction and rows C in a diagonal direction. The outer edges of said elevations are beveled or inclined, as at D. Between said elevations and between the several rows

are channels E and F, the bottoms of which 15 are flat.

I claim—

The design for surface ornamentation of walls, &c., substantially as herein shown and described, which consists of the flat-faced 20 rhombical elevations A, having inclined edges D, and disposed in rows B and C, with the intervening flat-bottomed channels E and F.

FREDERICK MANKEY.
